UNITED STATES PATENT OFFICE

ERSKINE E. BOYCE, OF CORONADO, CALIFORNIA

KNOTTER

Application filed May 2, 1928. Serial No. 274,536.

This invention relates to mechanism for tying a weaver's knot, and in the present preferred form takes the form of a hand knotter.

5 An object of the invention is to provide a simple and efficient knotter of novel and improved form in which a true weaver's knot is produced, and in which the mechanism performs all of the operations in producing said knot.

Further and more specific objects and advantages will more clearly appear from the detailed description following, taken in connection with the accompanying drawings, 15 which form a part of this specification.

Referring to the drawings, which illustrate the present preferred form of the invention:

Fig. 1 is a perspective view of the device, 20 Fig. 2 is a plan view of the device, with parts of the cover removed to better show the mechanism,

Fig. 3 is a front elevation of parts shown in Fig. 2,

25 Fig. 4 is a view on line 4—4 of Fig. 2, and showing one thread in position,

Fig. 5 is a section taken on line 5—5 of Fig. 2, with the mechanism in its starting position.

30 Fig. 6 is a section taken on line 5—5 of Fig. 2, with the mechanism shown in the position occupied during the latter part of its cycle of operation.

Fig. 7 is a section taken on line 8—8 of Fig. 2, with the mechanism in the position shown in Fig. 5,

35 Fig. 8 is a side elevation taken on line 8—8 of Fig. 2 with the mechanism in the position occupied at the end of the cycle of operation,

Figs. 9—19, inclusive, are views of parts of the mechanism in varying positions and illustrate the evolution of the knot.

Fig. 20 shows the form of the final knot produced on the device; but in open condition.

Referring to the drawings, and more particularly to Figs. 1 and 2: the main frame of the device, which supports the operating mechanism, comprises the side frame plates

1 and 2, which are suitably attached together in spaced relation by the block 3, to which the side plates are fastened by suitable means, and the pins 4, 5 and 7; to thereby present a substantially rigid supporting frame. A suitable handle 8 is attached to this frame, and cover plates, such as 9 and 10, (Fig. 1) are preferably provided for protecting the mechanism.

The plates 1 and 2 are provided respectively with opposite slots or notches 11, 12 and 13, 14, positioned slightly beyond the block 3; and the portions 15 and 16 separating the respective slots are brought to a point. The bottom of slot 12 is substantially lower than the bottom of slot 11, (see also Fig. 19); while the bottom of the slot 13 is substantially lower than the bottom of slot 14, and the bottom of the slot 13 is preferably offset as shown in Fig. 1. These slots serve to initially support in extended position, the strands of thread to be joined; as will be more fully explained hereinafter.

40 A driving member 17 (see also Figs. 5 and 6), which furnishes the motive means for operating the mechanism, is rotatably mounted on the spindle 18 by means of the sleeve 19 formed integral therewith and which sleeve is rigid with the spindle 18. The member 18 carries a gear rack segment 20 adjacent its periphery, and a cam portion having a cam face shoulder 21 and a cam face 22. The lever or trigger 23 is rigidly connected to the member 17 and provides means for rotating the driving member 17 in an anti-clockwise direction as viewed in Figs. 5 and 6. The stop 24 (Fig. 2) serves to limit the movement of the trigger to the desired throw, and a suitable spring (not shown) but preferably coiled about the sleeve 19, is provided for returning the trigger and member 17 to the starting position of Fig. 5.

45 A rotary driven shaft 25 is suitably journaled in the block 3 at its forward end and in bracket 26, attached to plate 1, at its rear end, and has secured thereto a collar 27. A pinion gear 28 is loosely mounted on the shaft 25 in mesh with the rack 20, and is restrained from forward axial movement

by the collar 27, and from rearward axial movement by a pin 29 extending from said shaft. The gear 28 is provided with a pin 30 extending rearwardly to engage the pin 29 for driving said shaft. A limit stop 31 is mounted on the bracket 26 and extends above pin 30 free from engagement therewith but in the path of movement of pin 29, and is adapted to yieldably limit the 10 rotation of the shaft 25 in a clockwise direction while permitting a greater degree of rotation in an anti-clockwise direction. A helical torque spring 32 surrounds the shaft 25 and is secured at one end to a pin 33 and 15 at the other end to the collar 27; being so formed that it is wound up upon the rotation of shaft 25 in an anti-clockwise direction, as viewed from the left of Figures 5 and 6, to thereby return shaft 25 in a clockwise direction.

A tying bill, which will be designated in its entirety as 34, comprises (Figs. 3 and 6) two outer jaws 35 and 36 between which is pivoted at 34' a movable jaw 37. The jaws 35 and 36 are provided with rearwardly extending portions which are rigidly attached to the shaft 25, as at the bearing member 38, which is journaled in the block 3; and the pivotal jaw 37 is provided with a rearwardly extending enlargement 37' whose rear end is seated in a circular bore formed in block 3 eccentric to the shaft 25, the eccentric being so formed that when the tying bill 34 is in the position shown in Figs. 2, 3 and 5, the pivotal jaw 37 will be in substantial register with the outside jaws 35 and 36, thereby assuming a closed position, and when the bill 34 reaches the position shown in Fig. 6, the jaws will be separated 40 as shown, and upon further rotation of the bill 34 in an anti-clockwise direction the jaws will again be closed, finally reaching the fully closed position when the jaw has assumed the position shown in Figs. 15 and 16.

Referring more particularly to Figs. 2, 4, 5 and 19: a hook 39 is attached to block 3 and projects forwardly therefrom with the hooked end projecting downwardly, and the top of the hook member is provided 50 with a downwardly gradually rounded upper portion. The opening in the hook is in line with slots 12 and 14, so that a thread line extended between slots 12 and 14 will lie in a plane passing through the hook.

A reciprocable member, in the form of a slide plate, 40, (Figs. 2, 5 and 6) is provided at its rear end with a slot 41 and at its forward end with a slot 42, and through these slots pass respectively the spindle 18 and the stud 4, thereby supporting the plate 41 while permitting it to reciprocate horizontally; the plate being positioned closely adjacent the side of the member 17. This plate is provided with an upper extension 43 (Figs. 5 and 6), to which is piv-

otally attached a cam latch 44 whose engaging jaw extends through a slot 45 and is normally resiliently held in positive driven engagement (Fig. 5) with the cam shoulder 21 by means of a leaf spring 46, (Fig. 2) so that the cam shoulder 21 will drive the plate 40 forward during a part of the rotation of the member 17. The latch is so positioned and the cam face 22 so formed that upon rotation of the driving member 17, the slide plate 40 will be moved forward until the latch 44 passes up onto the cam face 22 (Fig. 6), which is adapted to hold the plate 40 in its forward position until the latch passes over the rear end of the cam face 22; at which time a tension spring 47, whose forward end is attached to the plate 40 and whose rear end is attached to the pin 7, will retract the plate 40 to its normal position. The forward end 55 of the latch 44 is tapered or beveled to permit it to be moved outwardly by the rear side of the adjacent cam projection to thereby permit the driving member 17 to return to its normal position under the influence of the spring 42. The extreme forward end of plate 40 is provided with an upward extension 48, the upper end of which terminates in a hook 49 (Figs. 2 and 6). The hook 49 lies closely adjacent the rear side 95 of the hook 39, and when the parts are in the starting position, is in substantial alignment therewith as shown in Fig. 5.

An arm 50 is pivotally attached to the plate 40 as at 51 (Fig. 5) and is provided with a cam slot 52, through which extends a pin 6 rigidly supported by the block 3; the pivotal attachment 51 acting to impart reciprocal motion to the arm 50 and the slot 52 in cooperation with the pin 6 being 100 adapted to impart oscillatory motion to the arm 50; the arm 50 being movable in a slot in the block 3. The forward end of the arm 50 (Fig. 6) is provided with an offset downwardly extending end 53 terminating 105 in a bifurcation providing a pair of spaced upturned hooks 54, (Figs. 2, 4 and 19) which in the starting position are closely adjacent the front side of the hook 39, but somewhat below the hook 39 and in such 110 position that upon their upward movement they will engage a strand of thread passing between slots 12 and 14. A supplemental hook 55 (Figs. 2, 6 and 19) is attached to the end of the arm 50 and is offset laterally 115 and positioned somewhat above the hooks 54; the hook 55, the hooks 39 and 49 and the bottom of slot 12 being in substantial alignment at the start, and the hook 55 being positioned in a plane above the rearwardly 120 extending shank of the bill 34.

It is to be noted in this connection (Figs. 9 and 19) that a thread passing through slot 14 and over hook 55, beneath hooks 39 and 49 and through slot 12 adjacent the 125

bottom thereof will be so supported that a portion adjacent hooks 39 and 49 will be below the thread passing through slots 11 and 13.

5 A cutting and clamping device is mounted on pin 5 and is constructed in the following manner. The jaw members of this device will be designated collectively as 56 and comprise outer jaws (Fig. 2) 57 and 58 and an inner jaw 59 pivotally attached to the outer jaws (Fig. 6). The outer jaws are bent in U formation and are attached at their upper rearward end, designated as 60, to the rear plate 2 adjacent to the pin 5, (Fig. 3). The inner jaw extends downwardly and terminates in a laterally extending pin 60' which passes through a slotted opening in an operating lever 61, which is pivotally supported on pin 5, and which extends downwardly to the right as viewed in Figs. 5 and 6, then upwardly, terminating in an upper cam engaging end 62 adapted to be engaged by the cam shoulder 21. The arm 61 is normally resiliently held in the position shown in Fig. 5 by means of a helical torsion spring 63 mounted on the pin 5 and attached at one end to plate 1 and at the other end to the arm 61. In its normal position the arm holds the jaw 59 separated from the cooperating jaws 57 and 58 as shown in Fig. 5, thereby presenting the bill 56 in the open position when the device is in its initial position; and upon engagement 35 of the upper end 62 of the arm 61 by the cam shoulder 21 the jaws of the bill 56 are closed to thereby cut and clamp a thread extending therebetween. The bill 56 is so proportioned and positioned that the spaced hooks 54 will pass closely adjacent to, and one on each side of the bill 56 and into alignment with the opening in the bill.

A reciprocable slide member 64 (Figs. 2, 7 and 8) is slidably supported on pins 65 projecting inwardly from plate 2 and passing through a slot 66 formed in the member 64; and the member 64 is held in place on the pins 65 by means of a washer plate 67 held in position by suitable heads formed on the pin 65. The plate 64 passes through a slot in the block 3. The forward end of the member 64 projects downwardly and again upwardly in general U formation, and the upward outer side of the U is provided with a recess forming a slight hook 68 which at the start is in such position with respect to the slot 11 that a thread passing from the slot 11 across to slot 13 will be engaged by the hook 68. A recess 69 is formed in the other side of the U and is similarly positioned with respect to the bottom of slot 12.

The rear end of the member 64 is provided with a cam pin 70 which is adapted to be engaged by a cam finger 71 carried on cam 72, which is rigidly attached to axle 18,

to thereby provide for moving the slide member 64 to the left as viewed in Figs. 7 and 8, and the pin 70 is also in the path of movement of the cam projection 73 also formed as an integral part of cam 72 and 70 adapted upon engagement with the pin 70 to move the slide member 64 in the opposite direction.

A stripper arm 74 is pivotally supported, on a shaft 75, secured to the plate 2, and lies 75 closely adjacent to the side of the slide member 64. The forward end of the stripper 74 extends abruptly downwardly and outwardly and is provided with engaging hooks 76 and 77; the hook 76 being positioned to engage the thread passing through slot 12 and the hook 77 being positioned to engage the thread passing through slot 11. The rear end of the stripper 74 is provided with a cam engaging portion 78 adapted to be engaged by the cam finger 79 formed integral with the cam 72, to thereby provide means for lifting the stripper to the position shown in Fig. 8. A suitable tension spring 80 is attached at one end to the stripper arm 74 80 and at its other end to the plate 2, to thereby provide means for returning the stripper arm 74 to the position shown in Fig. 7. The stripper 74 in the starting position passes through a slot formed in the block 3. 85

It is to be understood, as will be appreciated by those skilled in the art, that the proper timing of the device will be in accordance with the following description of the operation of the mechanism; and that 100 the exact proportions and suitable formation of the parts will be arranged so that the device will operate in the manner now to be described.

Operation 105

The operative takes hold of the device by inserting the fingers of the left hand through the handle 8, with the opposite end of the device facing in a general direction toward him and with the thumb of his left hand in position to engage the trigger lever 23. The threads, —A— and —B—, to be joined are grasped with the right hand and extended across the device, on respectively opposite sides of the fingers 15 and 16 (Fig. 19), with the tails A' and B' passing out through the slots 14 and 13 respectively, and so that one thread —A— lies transversely of the tying bill, above and to the rear of the same, with the body of the thread projecting outwardly through slot 12 and the tail of the same projecting outwardly through slot 14, with the intermediate portion of the thread lying (Fig. 19) over the hook 55 behind the upwardly extending tip of the bill 34, over the rearwardly extending shank of the bill 34, over the hooks 54, and under the hooks 39 and 49; the thread being supported by hook 55. The other thread —B— is ex- 130

tended in a similar manner through and between the slots 11 and 13, across the shank of the bill 34, to the rear of the upwardly extending portion thereof, and forward of the various hooks above described, as viewed in Fig. 19. With the threads thus positioned in the device, the operative engages the trigger lever 23 with the thumb of his left hand and presses the same downwardly, thereby effecting the cycle of operation now to be more fully described in detail, with particular reference to Figs. 4 and 9 to 17, inclusive.

Upon the initial movement of the trigger 23, the driven member 17 is rotated forwardly and downwardly, thereby moving the cam shoulder 21 forwardly and downwardly and through its engagement with the latch 44, sliding the member 40 forwardly, resulting in simultaneously moving the hook 49 forwardly and in moving the hooks 54 and 55 first upwardly and then forwardly from the position shown in Fig. 4 to the position shown in Figs. 9 and 10. During this step the thread —A— remains engaged by the downwardly turned hook 39, to thereby hold that portion of the thread against upward and forward movement, while the adjacent portion of the same thread has been engaged by the hook 49 to move it forwardly underneath the thread —B—, and simultaneously the hooks 54 have engaged the thread at a point on the other side of the hook 39 to move it upwardly and across the top of thread —B— to thereby form a loop 81, the bight of which is engaged by the hook 39 and the open ends of which extend respectively on opposite sides of the thread —B—. This step also results in the hook 55 carrying the thread —A— over the top of the tying bill 34, as shown in Figs. 9 and 10, and that portion of the thread engaged by the hooks 54 has been moved forward and into the open jaws of the cutting and clamping bill 56. During this operation the threads are held by the fingers of the operative under slight tension but permitting the thread —A— to be drawn through the slot 12 to furnish the necessary length for movement of the thread to the position shown in Fig. 10. During the above movement of the driving member 17, the pinion gear 28 has been freely rotated substantially one revolution on its shaft 25 so that the pin 30 carried thereby is moved around to the opposite side of pin 29 without rotating the shaft 25.

The next step consists in giving further downward movement to the member 23 thereby causing pin 30 to engage pin 29 and rotate the shaft 25 and the bill 34 carried thereby to give them an initial rotative movement which carries the bill to the position shown in Fig. 11, during which time the slide member 64 is moved forward by

means of the mechanism hereinbefore described, thereby clamping the strands —A— and —B— against the side 2 as shown in Fig. 11. Upon further rotation of the bill, the forwardly extending open ends of the loop 81 are engaged by the tying bill, and as the bill moves down to the position shown in Fig. 12, the bight of the loop 81 is moved downwardly to thereby release the same from the hook 39. Upon further rotation of the tying bill 34, the loop 81 is moved by the bill 34, so that the bight of the loop 81 is in engagement with the adjacent portion of thread —B—, with the result that the loop 82 is formed in thread —B—, as shown in Fig. 13, and following this, the tail end of thread —B— as it slips over the elbow of the bill 34, is moved over and across the loop 81 to the position shown in Fig. 13. During this operation the jaws of the tying bill 34 have been opened and are ready to engage the tail end of thread —B—, the open jaws now lying directly beneath the tail of thread —B—. The cam latch 44 (Fig. 6) has now traveled up toward the end of the cam face 22, and upon further pressure on the trigger 23 passes over the end of the cam face to thereby permit the spring 47 to retract plate 40, thereby returning hook 49 and hooks 54 and 55 to their normal position as indicated in Fig. 14. At the same time the cam shoulder 21 comes into engagement with end 62 of arm 61 to thereby close the jaws of the cutting and clamping bill 56, so that the tail end of thread —A— will be held in position shown in Fig. 14. The tying bill 34 now engages the tail of strand —B— and the bills 34 and 56 substantially simultaneously cut off and clamp the respective tail ends of strands —B— and —A—, as shown in Fig. 15. During this operation the pin 29 engages the end of spring stop 31, and upon further movement, deflects the same, thereby allowing the bill to be moved slightly past its initial position: and also during this operation the cam finger 79 (Fig. 8) engages the rear end 78 of the stripper arm 74 to rotate the same upwardly to thereby engage threads —A— and —B— in the respective notches 76 and 77. Upon completing this movement of the trigger, the stripper arm 74 moves up to the positions shown in Figs. 16 and 17 to thereby pull the more or less completely formed knot 83 off the end of tying bill 34, and pull the tail end of thread —B— completely around loop 81 and back under the body of thread —B—.

The bills 34 and 56 still clamp the tails of the respective threads —B— and —A—, as the stripper arm 74 moves upwardly, pulling the body of the threads —A— and —B— as shown in Fig. 17, to thereby pull the knot taut. At this time the trigger arm 23 has moved to its maximum throw against

the stop 24, and upon being released by the operative, is returned to its normal position, by a suitable spring (not shown). The spring 32 rotates the shaft 25 to bring the 5 tying bill back to its normal position, which is definitely fixed by engagement of pin 29 with stop 31, which offers sufficient resistance against a force from this direction to counteract the unwound condition of spring 10 32. The other parts are returned to their respective normal positions by means hereinbefore described.

From an understanding of the above description in connection with the drawings, 15 it will be seen that I have provided a novel and useful device having means for supporting two threads in extended position across the device in respective slots 12—14 and 11—13, and both initially lying on the same 20 side of the tying bill 34, with one of the threads —A— releasably held in a position below the adjacent portion of the second thread —B— (Fig. 19) as by the fixed hook 39. The device is further provided with 25 means, the forwardly reciprocating hook 49 and the upwardly and forwardly reciprocating hooks 54, for moving portions of the first thread, which lie adjacent opposite sides of the holding means, respectively above and 30 below and transversely of the second thread, to thereby form a loop around the second thread, and for inserting one side of the loop in the normally open jaws of a cutting and 35 clamping device 56; and a means, such as as hook 55, is provided for lifting the first thread over and to the opposite side of the tying bill. Means is provided for rotating the tying bill to engage the sides of the loop formed in the first thread and for releasing 40 the bight of the same from the holding means, thereby allowing the bight to come into engagement with the adjacent portion of the second thread, which upon further rotation of the tying bill causes a loop to be 45 formed in the second thread, and the two threads to be partially coiled around the tying bill (Fig. 13). The tying bill is provided with cutting and clamping means and the jaws thereof are opened and brought 50 into a position where they engage the tail of the second thread to thereby cut and clamp the same (Figs. 14 and 15.) Means 64 is provided for clamping the body end of the two threads to the device during the formation 55 of the knot. The device is further provided with stripping means 74 to engage the body of the two threads between the tying bill and the respective points where they are clamped to the device, and the stripping 60 means comes into operation after the tying bill and the other cutting and clamping means have been moved to cut and clamp the two tails of the thread, (Fig. 16) and after the tail of the thread which is held in the 65 cutting bill has been passed partially around

the loop formed in the first thread. The stripper, upon further movement, pulls the partially formed loop upwardly from the tying bill, and thereby pulls the tail of the second thread, held in the tying bill, between 70 the two loops and under the second thread, and thereafter pulls the knot taut (Fig. 17). The various mechanisms of the device are automatically taken back to their respective normal positions after the operative releases the control trigger of the device, and the threads are thereupon released and may be removed from the machine properly joined together by a true weaver's knot. It will 75 therefore be seen that the device provides mechanism for carrying on all operations mechanically and in proper sequence, from the time that the threads are initially inserted into the device until the completion of 80 a true weaver's knot, as clearly illustrated in 85 the drawings.

Having thus described my invention with reference to its preferred form, it will be obvious, to those skilled in the art, after 90 understanding my invention, that various changes and modifications may be made therein without departing from the spirit and scope of my invention, and I desire to cover all forms and modifications coming 95 within the language or scope of any one or more of the appended claims.

What I claim is:

1. In a knitter, the combination of guides for supporting a first thread and a second thread, means for doubling said first thread transversely over the said second thread, and means for engaging said first thread, looping said second thread, and passing one end of the loop of said second thread through 100 one of said loops and forming a true weaver's knot.

2. In a knitter, the combination of means for looping one thread transversely around another thread, a tying bill positioned to rotate against said loop and arranged to shear and clamp one end of said other thread, and means for looping said cut thread around 105 said first loop.

3. In a knitter, the combination of means for looping one thread transversely around a second thread, a tying bill positioned to rotate against said loop and arranged to shear and clamp one end of the second thread, and means for looping said second thread around said first loop with the cut 110 end of said second thread passing between said second thread and said first loop, to thereby form a true weaver's knot.

4. In a knitter in combination, a tying bill having cutting and clamping means, means for supporting a thread across said bill, means for looping a second thread around said first thread with the sides of the loop extending beyond said first thread, 115 means for rotating said bill to engage the 120 125 130 135

sides of said loop and upon further rotation of said bill to cause the same to cut and clamp the tail of said first thread, and means for cutting the tail of said other thread.

5 5. In a knitter in combination, a tying bill having cutting and clamping means, means for supporting a thread across said bill, means for looping a second thread around said first thread with the sides of the loop
10 extending beyond said first thread, means for rotating said bill to engage the sides of said loop and upon further rotation of said bill to cause the same to cut and clamp the tail of said first thread, means for cutting the tail of said second thread, and means for
15 stripping said partially formed knot from said bill to thereby complete a true weaver's knot.

6. In a knitter in combination, a tying bill having cutting and clamping means, means for supporting a thread across said bill, means for looping a second thread around said first thread with the sides of the loop extending beyond said first thread and for holding said loop in position, means for rotating said bill to engage the sides of said loop and upon further rotation of said bill to cause the same to cut and clamp the tail of said first thread, and means for cutting the tail of said second thread.

7. In a knotter in combination, a tying bill having cutting and clamping means, means for supporting a thread across said bill, means for looping a second thread around said first thread with the sides of the loop extending beyond said first thread and for holding said loop in position with the bight of said loop positively held but releasably supported, means for rotating said bill to engage the sides of said loop and upon further rotation of said bill to cause the same to cut and clamp the tail of said first thread, and means for cutting the tail of said second thread.

45 8. In a knotter in combination, means for supporting a thread, means for looping a second thread around said first thread and for holding said loop positively supported with the bight thereof releasably held and
50 with the sides of said loop extending beyond said first thread, means for engaging the sides of said loop on the opposite side of the first thread from the bight of the loop and for releasing the bight from its support, and
55 means for cutting and for clamping the tail of said first thread.

9. In a knotter in combination, means for supporting a thread, means for looping a second thread around said first thread and
60 for holding said loop positively supported with the bight thereof releasably held and with the sides of said loop extending beyond said first thread, means for engaging the sides of said loop and for releasing the bight
65 from its support, means for cutting and for

clamping the tail of said first thread, and means for cutting the tail of said second thread.

10. In a knotter in combination, means for supporting a thread, means for looping a second thread around said first thread and for holding said loop positively supported with the bight thereof releasably held and with the sides of said loop extending beyond said first thread, means for engaging the sides of said loop and for releasing the bight from its support, means for clamping the body of both threads, and means for cutting and for clamping the tail of said first thread.

11. In a knitter, in combination, a rotary tying bill, means for supporting two threads on one side of said bill, means for supportingly engaging and releasably holding

supportingly engaging and releasably holding the first of said threads, means for moving portions of said first thread from the opposite sides of said holding means and across said second thread and respectively on opposite sides of the latter to thereby form a loop the bight of which is supported by said holding means and the two sides of which extend beyond said other thread and lie in the path of rotation of said bill.

12. In a knotter, in combination, a rotary tying bill, means for supporting two threads on one side of said bill, means for supporting

on one side of said bill, means for supportingly engaging and releasably holding one of said threads, mechanism for moving portions of said first thread from the opposite sides of said holding means to thereby form a loop the bight of which is supported by said holding means and the two sides of which extend beyond said second thread and lie in the path of rotation of said bill, said mechanism comprising, means moving upwardly and then transversely to the second thread to carry one of the portions of said first thread transversely over said second thread, and means moving transversely to said second thread to carry the other of said first thread portions transversely under said second thread.

13. In a knotter, in combination, a rotary tying bill having means for cutting and clamping the second of two threads, means for supporting said two threads at one side of said bill, means for supportingly engaging and releasably holding one of said threads, mechanism for moving portions of said first thread from the opposite sides of said holding means to thereby form a loop the bight of which is supported by said hold-

the sight of which is supported by said holding means and the two sides of which extend beyond said second thread and lie in the path of rotation of said bill, said mechanism comprising, means moving upwardly and then transversely to said second thread to carry one of the portions of said first thread transversely over said second thread, and means moving transversely to said second thread to carry the other portion of said

first thread transversely under said second thread, and cutting and clamping means positioned adjacent the path of movement of said upwardly moving means for cutting

5 the tail of said first thread.

14. In a knotter, in combination, a rotary tying bill, means for holding two threads across said bill on the same side thereof with one portion of one thread releasably held below the adjacent portion of the second thread, means for moving a portion of said first thread from one side of said releasably held portion and transversely beneath said second thread, and means for

15 moving a portion of said first thread from the other side of said releasably held portion over and transversely across said second thread.

15. In a knotter, in combination, a rotary 20 tying bill, means for holding two threads across, said bill on the same side thereof with one portion of one thread releasably held below the adjacent portion of the second thread, means for moving a portion of said first thread from adjacent one side of said releasably held portion transversely beneath said second thread, and means for moving a portion of said first thread from adjacent the other side of said releasably held portion over and transversely across said second thread and over and to the other side of said tying bill.

16. In a knotter, in combination, a rotary tying bill having cutting and clamping 35 means, means for holding two threads across said bill on the same side thereof with one portion of one thread releasably held below the adjacent portion of the second thread, means for moving a portion of said first thread from adjacent one side of said releasably held portion transversely beneath said second thread, means for moving a portion of said first thread from adjacent the other side of said releasably held portion over and transversely across said second thread and to the other side of said tying bill, and means for cutting the portion of said first thread which extends transversely over said second thread and for clamping

50 the cut end to hold it in position.

17. In a knotter, in combination, a rotary tying bill having cutting and clamping means, means for holding two threads across said bill on the same side thereof with one portion of one thread releasably held below the adjacent portion of the second thread, means for moving a portion of said first thread from adjacent one side of said releasably held portion and transversely beneath said second thread, means for moving a portion of said first thread from adjacent the other side of said releasably held portion and over and transversely across said second thread and to the other side of said tying bill, means for cutting

the portion of said first thread which extends transversely over said second thread and for clamping the cut end to hold it in position, and means including said bill for engaging said transversely extending portions to move them to thereby release said held portion and thereafter to loop said other thread about said first thread and to cut and clamp the tail of said other thread and loop it about said first loop and between

75

said first and second loops.

18. In a knotter, in combination, means for holding two threads in adjacent extended position, and mechanism for doubling one of said threads over the second to thereby form a loop extending around and transverse to said other thread, said mechanism including a first member to releasably hold the bight of said loop, a reciprocating member on one side of said first member, 80 and a reciprocating member on the other side of said first member.

19. In a knotter, in combination, means for holding two threads in adjacent extended position, mechanism for doubling 90 one of said threads over the second to thereby form a loop extending around and transverse to said second thread, and means for cutting the tail of said loop, said mechanism including a first member to releasably hold the bight of said loop, a reciprocating member on one side of said first member, a bifurcated reciprocating member on the other side of said first member for delivering said tail to said cutting means in adjacent supported position.

20. In a knotter, in combination, a rotary tying bill, means for holding two threads in adjacent extended position on the same side of said bill, mechanism for doubling 105 one of said threads over the second to thereby form a loop extending around and transverse to said other thread, means for cutting the tail of said loop, said mechanism including a first member to releasably hold the bight of said loop, a reciprocating member on one side of said first member, a bifurcated reciprocating member on the other side of said first member for delivering said tail to said cutting means in oppositely adjacent supported position, and means for lifting said first thread over said tying bill.

In testimony whereof I have signed my name to this specification.

ERSKINE E. BOYCE. 120
